SHEET METAL CONTAINER

Arthur Henry Blakeway, London, England, assignor to The Metal Box Company, Ltd., London, England, a corporation of Great Britain

Application July 15, 1936, Serial No. 90,808
In Great Britain November 25, 1935

2 Claims. (Cl. 220—64)

This invention relates to an improved metal container which is particularly adapted for the packaging of liquids. It is customary for such containers, after they are made, to be coated on the inside with a plastic material, such as paraffin wax which is so composed that it will not flake or craze when the container is stored at a refrigerating temperature or the walls of the container are accidentally bent or flexed through contact with each other or with refrigerating coils, ice or the like.

In applying the wax coating to the container, it is melted by heat, poured into the container and caused to contact with the entire interior surface thereof. The wax adheres to the metal surface and the surplus wax is drained from the container. The container is then cooled and is ready for filling.

Since it is customary in the packaging of beer and similar beverages to pasteurize the same after they are in the container, the wax is of such composition that it will not melt when raised to a temperature at or slightly above the pasteurizing temperature. The composition of the wax, however, is not a part of the present invention and need not be described here.

The object of the present invention is to form the seams of the container and adjacent portions of the body in such a manner as to promote the preservation of the unbroken surface of the coating under the conditions outlined above, and particularly during the pasteurizing process, when the volume of the liquid and its pressure upon the walls of the container are increased.

For this purpose, the side seam of the container is provided contiguous to its outer member with an inwardly extending rib, forming a gully between said rib and the opposed edge of the seam, in which gully an excess of coating material may be trapped to ensure complete coverage of the seam.

The specific construction of the invention in its preferred form, together with its advantages, will be particularly explained in connection with the accompanying drawing, in which,—

Figure 1 is a side elevation of a portion of a container constructed in accordance with the invention.

Figure 2 is a central sectional view of a portion of the container, showing an inner view of the side seam and gully.

Figure 3 is a similar view of the complete container after it is filled and sealed.

Figure 4 is a transverse sectional view of a

lock side seam constructed according to the invention.

Figure 5 is a similar view of a lap side seam constructed according to the invention.

As illustrated in Figures 1 to 4, the container 5 in which the invention is embodied comprises a body portion 1 made from sheet metal bent into cylindrical form with the meeting edges joined by a lock seam 2. A bottom end 3 is secured to the body portion 1 by a double seam 4 and the top end 5 is secured thereto by a double seam 6.

The top end 5 is represented in the present instance as having a dome 7 with an opening at its upper end, through which the container may be filled or the contents of the container dispensed. 15 The dome 7 is formed with a shoulder 9 terminating in a sealing lip 8, which is adapted to receive a crown seal 11. Within the crown seal 11 is a gasket 12, preferably of cork, which contacts with the lip 8 to provide an efficient hermetic seal which can readily be removed by an ordinary cap lifter without in any way injuring the container.

The wax coating, which is applied in the manner described above, is indicated at 10, and it 25 will be noted that this coating completely covers the side seam 2 and the double seams 6 and 4 at the top and bottom of the container. The container may be filled with the beverage and the seal 11 applied while the entire surface of the 30 coating is still in sterile condition.

In the packaging of certain beverages, such as beer for example, it is desirable to pasteurize the same after the container is sealed. In the usual process of pasteurization, the container is passed 35 through a water bath which is heated sufficiently to raise the temperature of the beverage to approximately 140° F. During this process, the expansion of the liquid imparts a considerable strain to the side seam. It is therefore essential 40 that a good coating of wax be assured along the inside edge of this seam. To this end, an inwardly extending rib 13 is formed in the can body contiguous to the outer member of the side seam 2. This rib extends longitudinally of the 45 seam and forms with the edge of this seam a gully 14, which will trap the coating material during the coating process and assure a full coating along the edge of the seam. The rib 13 preferably extends along the entire length of the 50 seam.

The body of the container may also be provided, contiguous to the inner member of the seam 2, with a bevel 15, which eliminates the sharp edge that would otherwise be presented 55

5 by the contiguous outer edge of the seam and also serves the purpose of relieving the strain on the side seam and obviates the tendency of the seam and the coating thereon to open as the volume of the liquid expands during the heating incident to the pasteurizing process. This bevel is formed along the line of greatest potential strain.

10 In the modification shown in Figure 5, 2^a indicates a lap seam or the lap portion of a lock and lap seam. In this modification, the inwardly extending rib 13 is also formed contiguous to the outer member of the seam 2^a, and with the edge of the seam forms a gully 14 similar to that 15 shown in Figure 4.

15 From the foregoing description, it will be seen that both the gully, formed between the rib 13 and opposed edge of the seam, and the bevel 15, formed by the inner portion of the seam, are important factors in assuring an unbroken interior wax surface not only during the pasteurizing process but also during the subsequent handling of the container.

20 While I have shown and described the invention with reference to a specific type of container, it will be understood that this is merely for the purpose of illustration and that both the top and the bottom of the container, as well as the manner in which they are secured to the body, and 25 also the construction of the side seam itself, may be modified in various ways, without any material departure from the scope of the invention, as defined in the appended claims.

30 Having thus described the invention, what I 35 claim as new and desire to secure by Letters Patent, is:—

1. A sheet metal container having a coating

of protective material applied to the inner surface thereof, said container including a body portion having the side edges joined by a solder bond, the outer member of the side seam being bent inwardly adjacent the side seam and longitudinally of the seam and thence bent gradually outwardly to merge into the peripheral line of the can body whereby sharp edges on the inside of the seam tending to cause weakness in the protective coating are eliminated and a gully is 10 formed between the inwardly bent portion and the seam, in which gully the coating material may be trapped to assure a good coating of protective material at the edge of the seam.

2. A sheet metal container having a coating of 15 protective material applied to the inner surface thereof, said container including a body portion having the edge portions joined by a solder bonded side seam, the body wall carrying the outer member of the side seam being bent inwardly 20 adjacent the side seam and longitudinally of the seam and thence gradually outwardly to merge into the peripheral line of the can body and the body wall carrying the inner member of the side seam being gradually bent outwardly to merge 25 into the peripheral line of the can body whereby sharp edges at the inside of the seam tending to cause weakness in the protective coating are eliminated and a gully is formed between the inwardly bent portion in the wall carrying the outer member and the edge of the seam, in which gully the coating material may be trapped to 30 assure a good coating of protective material at the edge of the seam. 35

ARTHUR HENRY BLAKEWAY.
